UNITED STATES PATENT OFFICE

149,114

DESIGN FOR A RECEPTACLE FOR COSMETICS AND OTHER ARTICLES

William A. Dion, North Attleboro, Mass., assignor to Evans Case Co., a corporation of Massachusetts

Application July 11, 1946, Serial No. 131,478

Term of patent 14 years

(Cl. D58—11)

To all whom it may concern:

Be it known that I, William A. Dion, a citizen of the United States, residing at North Attleboro, Massachusetts, have invented a new, original, and ornamental Design for a Receptacle for Cosmetics and Other Articles, of which the following is a specification, reference being had to the accompanying drawing, forming a part thereof.

In the accompanying drawing—

Figure 1 is a plan view of a receptacle for cosmetics and other articles showing my new design;

Figure 2 is a front elevational view of the same.

The projecting element at the center of the receptacle is transparent so that ornamentation underlying it is apparent through it.

The dominant features of my design reside in the portions of the drawing shown in full lines.

I claim:

The ornamental design for a receptacle for cosmetics and other articles, substantially as shown and described.

WILLIAM A. DION.
